INVENTOR.

Frederick M. Furber

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

SHOE AND METHOD OF MAKING THE SAME.

Application filed September 6, 1918, Serial No. 252,867. Renewed August 5, 1920. Serial No. 401,567.

To all whom it may concern:

Be it known that I, FREDERICK M. FURBER, a citizen of the United States, residing at Revere, in the county of Suffolk and State of Massachusetts, have invented certain Improvements in Shoes and Methods of Making the Same, of which the following description, in connection with the accompanying drawings, is a specification, 10 like reference characters on the drawings indicating like parts in the several figures.

This invention relates to the manufacture of shoes and more especially to improved methods of making the bottoms of 15 shoes. The invention is herein explained, for the purpose of illustration, as applied to the manufacture of shoes of the type in which the outsole consists of forepart and shank portions of superior stock terminating 20 a short distance rearwardly of the heel breast, and constituting a "short sole," and a sole extension member or heel portion, preferably of inferior stock, having its forward edge abutting against the rear end 25 of the outsole, the heel of the shoe covering the junction of the two members.

In producing soles of this kind it is very important to secure a connection between the abutting edge faces of the short sole 30 and the extension or heel member that will maintain a close and firm joint permanently since any separation of the two members and the consequent opening up of the joint will produce a crack appearing on the edge 35 surface of the sole so as to mar its finish and detract from the appearance of the shoe. A difficulty very often encountered is that the shrinkage which occurs after the shoe is made by reason of the moisture drying 40 out of the shoe tends to cause a separation between the two sole members and, with the methods now employed in assembling the two members, it is extremely difficult to prevent such shrinkage and consequent 45 damage to the shoe.

It is an object of the present invention to provide an improved method of assembling such members together which will not be dependent for satisfactory results 50 upon the skill and attention of the operative and which will offset to a large extent the effects of any shrinkage of the shoe stock when the shoe is completed.

In one important aspect this invention

provides for producing a tight and close 55 joint between the edges of a short sole and an extension member which consists in end fitting the short sole and the extension member to abut at their lateral edges and to provide clearance between them intermediate said edges, bringing the ends of the said members into juxtaposition and then relatively moving said parts heightwise to crowd said ends longitudinally together; 60

The invention in this and other aspects will be more fully understood from the following description with the aid of the accompanying drawings and will then be more definitely pointed out in the claims.

Fig. 1 of the drawings is a plan view of 70 a short sole and an extension member fitted to facilitate the practice of this invention;

Fig. 2 is a side elevation of a shoe in process of manufacture with the extension member, shown as attached to the shoe heel, about to be assembled with the short sole. 75

Fig. 3 is a view similar to Fig. 2 showing the parts assembled and permanently secured together.

A short outsole 1 of superior material, shown as attached to a shoe, including a welt, an upper and insole, and adapted to extend a short distance under the shoe heel. 80 It is slit at its rear end at 2 to provide marginal portions 3, 3 and an intermediate portion 4. The extension member or piece 5 for the sake of economy may be of inferior material and preferably is of approximately the same thickness as the combined outsole and welt and extends from the rear end of the heel to a line back of the heel breast. Either the intermediate portion of the sole between the slits 2 or the opposed portion of the extension member is cut away 85 as at 6 to provide clearance so that said intermediate portions offer no obstruction to a close contact of marginal portions 3, 3 with the extension member at the edge of the sole where the joint is exposed in the finished shoe. As herein shown, the sole is provided with a jig hole 10 to fit over the foremost of two jig pins 12 upstanding from the last or other support when the sole has been correctly located upon the bottom of the welted shoe and the marginal portions 3, 3 are left free when the sole 90 is stitched to the shoe. The extension 95

member is shown as attached to the heel before the latter is applied to the shoe, and the heel is shown as having jig holes 13 accurately located to fit over the pins 12 when the heel is in the right longitudinal relation to the shoe. Any other suitable system may be employed for restraining the sole member 1 and the extension member 5 from relative longitudinal movement 10 while they are being assembled.

For the purpose of more certainly securing a close joint between the sole and the extension member at their exposed edges, the marginal members 3, 3 are preliminarily 15 shortened as, for example, by being bent upwardly and forwardly as shown in Figs. 1 and 2. The parts are so proportioned that when brought together as in Fig. 2 the extension member may be lowered into contact with the upturned ends 3, 3, substantially touching but without overlapping the rear points thereof, and that when the heel is further lowered it bends downwardly and backwardly the ends 3, 3, which, because 20 they are already in abutting relation to the extension member, are crowded with a toggle-like action against the extension member to form a tight joint therewith. The heel is secured to the shoe while the 25 bottom members are in this relation, for example by attaching nails driven from the inside of the shoe as shown by dotted lines in Fig. 3.

Having explained the nature of this invention and described how it may be practiced, I claim as new and desire to secure by Letters Patent of the United States:—

1. That improvement in methods of making shoes which consists in providing a short 40 sole to extend under the heel breast, fitting its end to present upturned marginal corners and a recessed intermediate edge, providing a sole extension member to extend from the rear end of the heel to the short 45 sole, attaching the sole to a shoe, attaching the extension member to the shoe heel, providing the sole and the shoe heel with guiding surfaces adapted to be alined when the short sole and the sole extension are in the 50 right longitudinal relation to each other, bringing together the heel and attached extension member with a shoe having the attached sole until the extension member and the upturned corners abut, then guiding the 55 sole and the heel relatively by said surfaces while bending the upturned corners downwardly until the extension member is brought into the plane of the sole, and securing the heel to the shoe with the corners 60 crowded against the extension member.

2. That improvement in methods of making shoes which consists in forming a short sole and an extension member with upturned corners and constructed and arranged to provide clearance between the cor-

ners of their adjacent ends, abutting said ends with the upturned corners in engagement, restraining the short sole and extension member from relative lengthwise movement while forcing the upturned corners down into the plane of the sole during continued abutting engagement of the ends, and fastening the short sole and the extension member together with the corners under the endwise compression effected by the described procedure.

3. That improvement in methods of making close joints between the edges of short soles and extension members which consists in slitting the short sole from its end forwardly a short distance inward from each edge and upturning the marginal members thus produced, relatively constructing and arranging the portion of the short sole between the marginal members to provide clearance between said portion and the adjacent end of the extension member, and forcing the marginal members and the extension member into the plane of the short sole while said members are held in end-abutting relation.

4. That improvement in methods of making close joints between the edges of short soles and extension members which consists in end fitting said parts to abut at their lateral edges and have clearance between said edges, upturning the lateral edges of one of said parts, abutting adjacent ends of said parts, and forcing them into the plane of the sole while restraining the parts from relative endwise displacement.

5. That improvement in methods of making close joints between the edges of short soles and extension members which consists in slitting a short sole from its end forwardly a short distance inward from each edge and upturning the marginal members thus produced, relatively constructing and arranging the portion of the short sole between the marginal members to provide clearance between said portion and the adjacent end of the extension member, threading the short sole and a holder for the extension member on a guide adapted to restrain said parts from endwise displacement, and forcing said parts relatively along said guide with the extension member and said upturned members in abutting relation until the extension member is in the plane of the short sole and the upturned members have simultaneously been turned down into said plane.

6. That improvement in methods of making close joints between the edges of short soles and extension members which consists in slitting a short sole from its end forwardly a short distance inward from each edge and upturning the marginal members thus produced, relatively constructing and arranging the portion of the short sole be-

tween the marginal members to provide clearance between said portion and the adjacent end of the extension member, attaching the extension member to a heel, providing the heel and the intermediate portion of the sole with holes located to be in endwise alinement when the sole and heel are assembled, threading the sole and the heel on a guide pin, and forcing the heel down and causing the extension member first to be alined with said upturned members and thereafter forcing the heel down until said members have been turned down and caused to crowd against the abutting end of the extension member.

7. That improvement in methods of making shoes which comprises fitting the adjacent ends of a short sole and an integral extension member to abut at their lateral edges and to provide clearance between them intermediate said edges, bringing said ends into juxtaposition and then relatively moving said parts heightwise to crowd said ends longitudinally together.

8. That improvement in methods of making shoes which comprises fitting the adjacent ends of a short sole and an extension member to abut at their lateral edges, securing the sole to a shoe, bringing said ends into juxtaposition, and then, while moving said parts relatively in the general direction of the height of the shoe, crowding said ends longitudinally together.

9. That improvement in methods of making shoes which comprises forming a short sole with end portions at opposite sides out of the final position they are to occupy in the finished shoe and with an intermediate portion cut away between said end portions, bringing said end portions into juxtaposition with relation to an extension member which constitutes a portion of a heel, attaching the heel to the shoe and, as a part of such operation, forcing said end portions into final position.

10. That improvement in methods of making shoes which comprises forming a short sole with end portions constructed and arranged to abut against an extension member at opposite margins thereof, said portions being also out of the final position which they are to occupy in the finished shoe, securing said sole to the shoe, applying the extension member and a heel to the shoe and forcing said end portions into their final position and then securing the heel, the

extension member and said end portions permanently in such position.

11. That improvement in methods of making shoes which comprises fitting the adjacent ends of a short sole and an extension member to abut at their lateral edges, threading them on a guide adapted to restrain them from relative endwise displacement, forcing said parts relatively along said guide to bring them into alinement in abutting relation and securing them permanently to a shoe in such relation.

12. That improvement in methods of making shoes which comprises providing a shoe with a short outsole, securing a sole extension member to a heel as a part thereof, upturning the rear end of the outsole, engaging said extension member with said upturned end, forcing the heel into place with a toggle-like action between the heel and the end of the outsole to bend said end toward the shoe and insure a close joint between the outsole and heel, and securing the heel to the shoe while the parts are maintained in such relation.

13. That improvement in methods of making shoes which comprises slitting a short sole from its rear end forwardly at a short distance from each edge, deflecting the marginal portions thus produced out of the final position they are to occupy in the finished shoe, then bringing said portions into juxtaposition with relation to an extension member which constitutes a portion of a heel, attaching the heel to the shoe and, as a part of such operation, forcing said portions into final position.

14. That improvement in methods of making shoes which comprises fitting the adjacent ends of a short sole and welt and also an extension member to abut at their lateral edges, bringing said ends into juxtaposition, said sole and welt being secured to a shoe and said extension member to a heel, and then relatively moving said parts to crowd said ends longitudinally together.

15. A welt shoe having a bottom comprising a short sole and a heel including a sole extension member with a straight end, said sole having marginal portions 3, 3 abutting firmly against said end, and a cutaway portion 6 affording clearance between said marginal portions.

In testimony whereof I have signed my name to this specification.

FREDERICK M. FURBER.
